Primary Examiner — Jonathan J Han*Assistant Examiner* — Caitlin MacKenzie Williams(74) Attorney, Agent, or Firm — Amy Fiene; James SonntagCLAIM

The ornamental design for a assistive garment, as shown.

DESCRIPTION

FIG. 1 is a front view of an assistive garment showing my new design in a position of use;

FIG. 2 is a back view thereof;

FIG. 3 is a perspective view thereof;

FIG. 4 is a perspective view thereof; and,

FIG. 5 is a top view thereof.

The broken lines depict features of the assistive garment that form no part of the claimed design.

1 Claim, 5 Drawing Sheets(56)
